RECEPTACLE ATTACHMENT FOR AUTOMOBILE VISORS

Casper Catanese, Cleveland, Ohio

Application August 18, 1949, Serial No. 4,595

Term of patent 14 years

(Cl. D14—6)

To all whom it may concern:

Be it known that I, Casper Catanese, a citizen of the United States, residing at Cleveland, in the county of Cuyahoga and State of Ohio, have invented a new, original, and ornamental Design for a Receptacle Attachment for Automobile Visors, of which the following is a specification, reference being had to the accompanying drawing, forming a part thereof, wherein:

Figure 1 is a top plan view of a receptacle attachment for automobile visors embodying the design of my invention.

Figure 2 is an end elevation of the same.

Figure 3 is a side elevation of the same.

Figure 4 is an end elevation of the same looking toward the opposite end from that shown in Figure 2.

Figure 5 is a side elevation of the same looking toward the opposite side of that shown in Figure 3.

Figure 6 is a bottom plan view of the same.

I claim:

The ornamental design for a receptacle attachment for automobile visors, as shown.

CASPER CATANESE.
